WELL PUMPING APPARATUS

Roland Plotts, Carlyle, Ill.

Application October 9, 1940, Serial No. 360,506

8 Claims. (Cl. 74—593)

This invention relates to improvements in well pumping equipment.

The primary object of this invention is the provision of an improved safety throw-off mechanism for well pumping equipment.

A further object of this invention is the provision of improved safety means for operating the throw-off or safety connecting means in pump lines.

Other objects and advantages of this invention will be apparent during the course of the following detailed description.

In the accompanying drawing, forming a part of the specification, and wherein similar reference characters designate corresponding parts throughout the several views,

Figure 1 is a plan view of the improved portion of pumping apparatus such as is used in multiple pull line pumping equipment.

Figure 2 is a side elevation of the improved portion of the pumping equipment.

Figure 3 is a view similar to Figure 2, but partly in section, showing the power line disconnected from the pull rod section of the pumping equipment.

Figures 4 and 5 are cross sectional views taken substantially on their respective section lines shown in Figure 2 of the drawing.

In the accompanying drawing, wherein for the purpose of illustration is shown a preferred embodiment of the invention, the letter A may generally designate the power line of pumping equipment, connected detachably to a pull line B by means of safety connecting means C. Means D is provided to support the power line A adjacent the connection C. An improved safety operating mechanism E for the safety connecting means C.

The power line A leads off from any approved power source, such as a pumping pendulum, walking beam, or eccentric power unit. It terminates adjacent the safety connecting means C in a hook shaped section 15 having a detachable connection 16 with the power line A. To this connection 16 is also connected a traveling block 17 which slides rectilinearly in the supporting means D. The hook section 15, as is usual, terminates in a hook end 20.

Referring to the supporting means D, the same is intended to slidably support the pump line A adjacent to the safety connection C, so the section 15 will have a true rectilinear sliding movement; the connection 16 forming an axis which will permit of some side play of the power line A.

The support D further includes a base 25 having relatively spaced side rails 26 and 27 con-

nected in spaced relation thereabove by means of U-shaped bracket portions 28. They are spaced to provide a channel 29 in which the power line section 15 slides and is guided. The travel block 17 slides in the space between the base 28 and the rail sections 26 and 27. Posts 35 and 36 are provided at the ends of the base 28 for supporting the latter by angles 37.

Referring to the safety connecting means C, the same includes a hook-shaped connecting link 50, pivoted at 51 to the pull line, as by means of a yoke 52. The link 50 is referred to as hook-shaped, but it is hook-shaped only in the sense that it provides a diagonal recess or opening 53 shaped to receive a detent loop 55 in order to hold the pull rod or line B inoperative, in the position shown in Figure 3.

The safety connecting means C further includes a loop member 60 which is in the form of an elongated loop provided with an opening 61 longitudinally therealong in which the hook end 20 of the power line may ride, as when the pull line B is held inoperative by the safety hook-off or detent 55. Normally, the hook end 20 engages the end of the loop 60, as shown in Figures 1 and 2, when the hook line is in full operating position. The loop member 60 is pivoted to the free end of the link 50 at 64.

The hook-off detent 55 is of elongated loop-shaped formation, providing side legs, the free ends of which are pivoted at 70 to the top of the post 36, and the bight end of which is adapted to hook in the recess 53 of the connecting link 50 in order to hook-off the pull rod line from the power line.

It must be borne in mind that the pull rod section B and the parts of the safety connecting means C are rather heavy. Releasable safety connections have heretofore been provided. Because of their weight and complicated nature they have been difficult to operate. Several of them are extremely dangerous to those whose duty it is to hook them on and off, as is well known to those skilled in the art to which this invention relates. To obviate such difficulties I have provided the improved supporting and operating means E. It serves a number of functions, namely, that of supporting the hook-off detent 55 in position for ready attachment, as shown in Figure 2; that of permitting lifting of the detent 55 into a hook-off position with respect to the connecting link 50; and that of lifting the loop 60 from inactive position to a position where it may hook onto the power line, when it is desired

to place the pumping line in well pumping operation.

The safety operating mechanism E includes a bell crank operating lever 80, releasably pivoted in a socket provided at the upper end of a supporting post 81, as by cross portion 82 (shown in Figure 5 of the drawing) which connects the handle portion 84 and the operating lever portions 85 and 86. The operating lever portions 85 and 86 extend at both sides of the pivot axis of the bell crank lever. The portion 85 projects in the direction of the pull line B, and parallel therewith, and the portion 86 projects in the direction of the power line A. The extreme end 87 of the portion 86 is acutely down-turned at its free end and is provided with a lateral pin extension 91, shown best in Figure 1 of the drawing, which normally is in position to engage beneath the detent loop 55 and assists in supporting loop 5 in horizontal position. It should be noted that the lever portions 85 and 86 are in the same line and alongside and in parallel relation with the adjacent leg of the loop of the detent 55. The detent 55 at its free end is provided with a pin extension 92 which normally engages upon the free end of the lever portion 85, so that when the latter is moved upwardly it will lift the strap detent loop 55 into position to engage in the hook end of the link 50 to throw off the power line from the pull line.

In operation the power and pull lines are connected as shown in Figure 2 of the drawing. If it is desired to disconnect the pull line from the power line it is merely necessary to move the handle 84 of the bell crank lever 80 forwardly in the direction of the power line, and this will swing the bell crank lever end 85 upwardly, engaging the pin 92 and moving the detent 55 into position for hooking into the connecting link 50. Power line section 15 will then move forwardly and release its hook end 20 from the strap loop 60. The latter will drop to the position shown in Figure 3 of the drawing; its pin end 100 engaging and resting upon the top of one of the legs of the detent 55, and it will be supported in the position shown in Figure 3. When it is desired to disconnect the detent loop 55 and place the power and pull lines in operating connection, it is merely necessary to swing the bell crank lever 80 so that its lever end 86 engages the pin 100 upon the strap loop 60 and lift the loop at the forward end of the movement of the power line and into position to engage in the hook end 20 of the power line. The detent loop 55 is horizontally positioned in readiness to safely disconnect the power and pull line at all times due to the fact that pin 91 engages beneath the loop 55 at one side of the axis of the bell crank 80 and the pin 92 rests on top of lever 85 at the other side of said axis, as shown in Figure 2 of the drawing.

Various changes in the shape, size and arrangement of parts may be made in the form of invention herein shown and described, without departing from the spirit of the invention or scope of the claims.

I claim:

1. In well pumping equipment the combination of a power line, a pull line, a releasable safety connection between the power and pull lines including a hook line pivotally connected with the pull line and a loop pivotally connected with the hook line and adapted to be engaged by the power line for effecting a connection of the pull and power lines, a movable detent for engaging

the hook link of said safety connection to hook off the pull line from the power line, and lever means for manually moving the detent into operating connection with said link of the safety connection and for also moving the loop of said safety connection from an inoperative position into connected relation with the power line.

5 2. In well pumping equipment the combination of a power line, a hook section connected on a vertical pivot axis at the end of the power line, an elongated supporting stand, means upon said stand and the pivot axis aforesaid positioning the power line and its hook section upon said stand for rectilinear sliding therealong.

10 3. In well pumping equipment the combination of a power line, a hook section connected on a vertical pivot axis at the end of the power line, an elongated supporting stand, means upon said stand and the pivot axis aforesaid positioning the power line and its hook section upon said stand for rectilinear sliding therealong, and a pivoted hook-off detent connection associated with said stand in a fixed pivoted relation.

15 4. In pumping apparatus, a power line, a pull line, a hook-shaped link pivoted with the pull line, a loop link pivoted at the free end of the hook link, a pivoted detent loop pivoted on a fixed axis for connection with the hook link to hook off the pull line from the pump line, a bell 20 crank lever including a handle portion and operating lever portions extending to both sides of the pivot axis of the bell crank lever, a pin extension upon the free end of the detent resting upon the top of one of said lever portions at one 25 side of the pivot axis of the handle of the bell crank lever so that upon movement of the bell crank lever the detent may be moved into position for engaging the hook link aforesaid to disconnect the pull line from the power line, and a pin extension laterally projecting from the loop link of said connection in position to be engaged by the other lever portion of said bell crank lever whereby the said loop may be moved into position to effect a power connection of the power and pull lines.

30 5. In well pumping equipment the combination of a power line, a pull line, a safety connection between the power and pull lines including a part pivoted to one of said lines adapted to releasably engage the other of said lines, a movable detent adapted to releasably hook onto the pull line to hold the same inoperative with respect to the power line, and a single means for moving both said part of the safety connection and said detent into operating positions.

35 6. In well pumping equipment the combination of a power line, a pull line, a safety connection between the power line and pull line, a part pivotally connected to one of said lines and adapted to releasably engage the other of said lines, a movable detent adapted to releasably engage the pull line to hold the latter inoperative, a pivoted handle, and levers connected with the handle for movement therewith, and in position to move the pivoted part of said safety connection into operating connection of the power and pull lines and to move the detent into an operative hook-off position with the pull line.

40 7. In well pumping equipment, the combination of a power line, a pull line, a hook section connected on a vertical pivot axis at the end of the power line, an elongated supporting stand, means upon said stand and pivot axis aforesaid positioning the power line and its hook section upon said stand for rectilinear sliding there-

along, a loop pivoted upon the pull line section for connection with the hook section of the power line, a pivoted hook off detent connected upon said stand, and means provided upon the pull line for receiving the pivoted hook off detent to hold the pull line inoperative upon disconnection of the hook section and loop link of said power and pull lines.

8. In well pumping equipment, the combination of a power line, a pull line, a releasable connecting link pivoted to one of said lines and adapted to releasably hook upon the other line

to effect a connection of said lines, a pivoted detent, an operating lever, means pivotally mounting the operating lever, said lever having an arm portion extending to one side of its pivot axis in position for operatively moving the detent into a hook off connection with one of said lines, and an arm portion on the lever extending to the opposite side of the lever pivot axis for operatively moving the said connection link from an inoperative position to an operative connection of said pull and power lines.
